UNITED STATES PATENT OFFICE.

ELWIN T. DAVISON, OF ATHENIA, NEW JERSEY.

CUTLERY SHARPENER.

Application filed March 19, 1925. Serial No. 16,660.

To all whom it may concern:

Be it known that I, ELWIN T. DAVISON, a citizen of the United States, and a resident of Athenia, in the county of Passaic and State of New Jersey, have invented new and useful Improvements in Cutlery Sharpeners, of which the following is a specification.

This invention relates to devices for sharpening various articles of cutlery and more particularly is adapted for sharpening of shears, pocket knives and table knives and has for its principal objects the provision of a cheap, compact and effective device for accomplishing the aforesaid purposes. I am aware that various cutlery sharpeners have been proposed wherein files or abrading devices have been secured in a sharpening block and the configuration of the block was such as to guide the blade of the article to be sharpened so it would be presented at a predetermined angle to such abrading surface. My invention refers to certain important additional features not disclosed in the prior art whereby the effectiveness of the device is increased, the same being fully set forth in detail in the following description and drawings forming a part thereof in which

30 Figure 1 is an elevation;

Fig. 2 is a section along the line 2—2 of Fig. 1;

Fig. 3 is a transverse section along the line 3—3 of Fig. 2; and

35 Fig. 4 is a view similar to Fig. 3 but showing a different type of blade being sharpened.

Referring to the drawings and the construction shown therein, reference numeral 1 designates an elongated hollow body, preferably formed of sheet metal, which is provided with integral base flanges 2, 2' which are adapted to be secured to a suitable support 3 by means of screws 4 inserted through

45 apertures 5 and slots 5', the latter permitting of adjustment of the base members to vary the cross-sectional area of the body 1 in order to accommodate abrasive implements of varying sizes as hereinafter referred to.

50 Immediately above the contracted portion of the body 1, is a portion 6 of triangular cross section throughout the entire length of the body and above this portion is a bonnet portion of substantially U-shaped cross section as designated by the reference numeral

55 7. An abrasive implement comprising a file

or other abrasive, such as a strip of corundum, as designated by the reference numeral 8, is adapted to be inserted in the body portion 6 and by suitable adjustment 60 of the base flanges, the same can be tightly secured against movement within such portion 6 of the body. Preferably, as shown in Fig. 1, the bonnet portion 7 is provided with two recesses having a predetermined configuration, each having walls b, b' which are adapted to conform to the proper angle for guiding the blade of a pair of scissors, so that the cutting edge will engage the abrasive on its upper surface at the exact 65 angle required to produce the most effective results in such an implement. At the bottom of such recesses, the side walls of the bonnet are cut away to form an aperture c and thus prevent the cutting edge of the implement being sharpened from striking the 70 walls of the implement. This aperture is located at the terminus of the sloping walls 9 or the sloping walls 9' of said recess, which walls are adapted to conform to the 75 exact angle viz: not exceeding 45° and preferably, as shown in the drawings, considerably less than 45°, which is required to support the butt end of a knife blade (see Fig. 80 3) in a proper position so as to maintain the cutting edge of such blade in proper relation to the upper surface of the abrasive 8. The edges d, d' of the recesses are adapted to project to the exact point required to prevent a knife blade, such as y, 85 from penetrating into the aperture c sufficient to permit its cutting edge to contact with the rear or vertical walls 10, 10' of such aperture, and at the same time such edges 90 form the lower edge of the faces b, b', which as stated, serve to guide the blade of a pair of scissors, such as x, (see Fig. 4) and maintain the same in proper relation to produce an effective cutting edge thereon. 95

In Fig. 3 the abrasive implement as shown, as designated by the reference numeral 8, is a file, whereas in Fig. 4 the abrasive implement shown is of corundum. Either of these implements may be inserted so as to project into each of the recesses c shown in Fig. 1, although preferably in one recess I provide an implement of corundum for finishing the sharpening operation after the blade has been sharpened on a file inserted 105 in the other recess c.

110 The operation of my improved sharpener,

as is evident from the foregoing description, is as follows:—

After an abrasive implement has been inserted in the body 6 of the implement, preferably a piece of a file being inserted beneath one of the recesses *c* and a piece of corundum being inserted beneath the other recess *c*, a blade of a pair of shears is rapidly drawn back and forth across the abrasive surface while the side of such blade is held in intimate contact with the face *b* or *b'* of the bonnet. When sharpening a knife blade, as designated by the reference letter *y*, the same is held in the position shown in Fig. 3 and rapidly drawn back and forth across the abrasive surface, then being turned over and rapidly drawn back and forth an equal number of times until the opposite edge of the blade is similarly sharpened.

This type of sharpener has among its advantages its extreme compactness and cheapness and the fact that it can accommodate abrasive implement which varies considerably in size, it merely being necessary to adjust the distance of the flanges with respect to each other by loosening the screw 4 which projects into the slot 5, and after the adjustment has been effected, such screw is then tightened, thus rigidly holding the abrasive implement within the body 6.

Preferably the body of the sharpener is formed from sheet iron of about 26 gauge, which may be copper or nickel plated if desired. The metal should not be too thick, however, as not to be yieldable as it is highly advantageous to have the body sufficiently yieldable or elastic to permit of abrasive implements of varying sizes to be inserted within and firmly held or retained by the opposing walls of the recess 6.

Obviously the abrasive surface may be renewed by merely moving a fresh area thereof beneath one of the recesses *c* and furthermore, the abrasive implement can be turned over to expose a fresh side thereof when one side has become worn.

Having thus described my invention, what I claim and desire to procure by United States Letters Patent is:

1. In a sharpener for cutlery, the combination comprising a body member having a chamber therein for receiving an abrasive implement, a superstructure above said chamber, said superstructure being rigidly secured to said body member and being slotted to form a recess which has an inner rear wall and sloping entrance walls, one of

which entrance walls projects substantially less than 45° with respect to the upper face of an abrasive implement when mounted in 60 said body member and at a proper angularity to guide a knife blade against such abrasive implement in order to most effectively sharpen the same and another wall of said recess extending at an angle to the aforesaid 65 wall and serving as a guide for the blade of a pair of scissors during the sharpening operation so as to maintain such blade at a predetermined angularity in respect to said abrasive implement and the lower edge 70 of said wall being adapted to engage the side of a knife blade when the latter is being sharpened in said sharpener and to thereby prevent the cutting edge of said knife blade engaging a wall of said recess 75 during the sharpening thereof.

2. In a combination sharpener for shears and knives, comprising an elongated hollow body of elastic metal having two opposing lateral members integral therewith which are adapted to be adjusted within the elastic limits of the metal with respect to each other, an abrasive implement snugly held within said body member and said body being provided with a superstructure integral 85 therewith, which superstructure is slotted so as to form a recess which has an inner rear wall and sloping entrance walls, one of 90 which entrance walls conforms to the angularity, and being substantially less than 45° with respect to the face of such abrasive implement when mounted in said body, which is required to guide a blade of a pair 95 of shears at the proper angularity with respect to the upper face of an abrasive implement held in said body and the other of which serves as a guide to hold a knife 100 blade at a predetermined angularity with respect to such abrasive implement in order to obtain the most effective sharpening thereof when such knife blade or blade of a pair of shears is being drawn across such abrasive implement and the lower edge of said 105 first mentioned entrance wall being adapted to project into the path of a knife blade held against the other wall during the sharpening operation so as to engage the upper face of such knife blade and to prevent the edge thereof from striking the said rear wall 110 of said recess.

Signed at New York in the county of New York and State of New York this 18th day of March 1925.

ELWIN T. DAVISON.
